(57) **CLAIM**

The ornamental design for a high-lumen round light fixture, as shown and described.

DESCRIPTION

FIG. 1 is a top perspective view of a high-lumen round light fixture, showing our new design;

FIG. 2 is a bottom perspective view thereof;

FIG. 3 is a side view thereof, the other side views being the same as that shown in FIG. 3;

FIG. 4 is a top plan view thereof; and,

FIG. 5 is bottom plan view thereof;

The broken lines shown on the drawings depict portions of the light fixture that form no part of the claimed design.
